UNITED STATES PATENT OFFICE.

OTTO A. HENSEL, OF PITTSBURG, ASSIGNOR, BY MESNE ASSIGNMENTS, TO THE DIAMONDUM NOVELTY COMPANY, OF ALLEGHENY, PENNSYLVANIA.

DESIGN FOR A FRAME FOR GRINDING-MACHINES.

SPECIFICATION forming part of Design No. 24,800, dated October 29, 1895.

Application filed May 28, 1895. Serial No. 551,019. Term of patent 7 years.

To all whom it may concern:

Be it known that I, OTTO A. HENSEL, a citizen of the United States, residing at Pittsburgh, in the county of Allegheny and State of Pennsylvania, have invented and produced a new and original Design for a Frame for Grinding-Machines, of which the following is a specification, reference being had to the accompanying drawings, showing a part thereof, and in which I have shown a perspective view of my design which is in accordance with my invention.

In the drawings forming part of this specification, Figure 1 is a view in perspective of my design. Fig. 2 is a sectional view taken on the line $x-x$ of Fig. 1, and Fig. 3 is a sectional view taken on the line $y-y$ of Fig. 1.

The leading feature of the design consists in a dovetail foot 1, a shank 2, extending out-

wardly therefrom and provided with ribs 3, 20 making it approximately T-shaped in cross-section and terminating in a double boss 3 and 4 with an intermediate space, while integral with the upper boss 4 is a flat extension 5, provided with ribs 6 and bosses 7, and projecting from the vertical partition 5 at an oblique angle is a thin integral portion with a slot extending inwardly.

What I claim is—

The design for a grinding machine frame 30 substantially as herein shown and described.

In testimony whereof I affix my signature in presence of two witnesses.

OTTO A. HENSEL.
